Primary Examiner — T Chase Nelson*Assistant Examiner* — Kelly L Gross(74) *Attorney, Agent, or Firm* — Fox Rothschild LLP(57) **CLAIM**

The ornamental design for an incontinence article, as shown and described.

DESCRIPTION

FIGS. 1 is a top perspective of an ornamental design for an incontinence article;

FIG. 2 is a top plan view of the article of FIG. 1;

FIG. 3 is a side elevational view of the article of FIG. 1;

FIG. 4 is a bottom plan view of the article of FIG. 1.

FIG. 5 is a perspective top view of the article of FIG. 1 in an expanded state; and,

FIG. 6 is a perspective view of the article of FIG. 1 in an expanded state.

The broken lines illustrate environmental structure associated with the incontinence article in a condition of use. The broken lines and structure they depict form no part of the claimed design.
